DESIGN FOR AN ELECTRIC BROILER OR THE LIKE

Herbert E. Brannon, Detroit, Mich.

Application November 15, 1939, Serial No. 88,296

Term of patent 7 years

To all whom it may concern:

Be it known that I, Herbert E. Brannon, a citizen of the United States, residing at Detroit, in the county of Wayne and State of Michigan, have invented a new, original, and ornamental Design for an Electric Broiler or the like, of which the following is a specification, reference being had to the accompanying drawing, forming a part thereof.

In the drawing:

The single figure is a perspective view of the electric broiler embodying my new design. The back side of the broiler is identical in appearance to the front side, and the left end is identical in appearance to the right end.

I claim:

The ornamental design for an electric broiler or the like, substantially as shown and described.

HERBERT E. BRANNON.
